CONVEYER FOR GRAIN BINDERS

Asle Seppola, Evansburgh, Alberta, Canada

Application January 14, 1947, Serial No. 722,000

4 Claims. (Cl. 24—32)

1

This invention relates to canvas conveyors for grain binders whether of the apron or elevator type.

There are two objectionable features in conventional conveyors of this general type. The first is that the buckle arrangement, whereby the two ends of the canvas are joined together, is unsatisfactory. It is not conveniently and practically possible to adequately tighten conventional conveyors upon their rollers with the buckles now in use. The second objectionable feature lies in the fact that the free flap of conventional canvas conveyors which is employed to cover the gap between the two ends of the conveyor as well as to cover the buckle construction is inadequately controlled during conditions of actual operation of the binder.

It is accordingly one of the principal objects of this invention to provide a satisfactory buckle construction whereby the canvas conveyor may be properly tightened upon its rollers.

It is another principal object of this invention to provide a flap control mechanism which cooperates with the buckle construction to properly and adequately control the free flap of the canvas conveyor.

The improvements herein claimed are adapted to be used in connection with conventional equipment without substantially modifying the equipment.

Other objects and advantages of the improvements herein claimed will be apparent from a reading of the following description:

Preferred embodiments of this invention are shown in the accompanying drawing in which—

Fig. 1 is a plan view of a canvas conveyor mounted on its rollers and incorporating the features of the present invention, said conveyor being partly broken away at the buckle construction to expose said construction as well as the flap holding mechanism;

Fig. 2 is a side view thereof;

Fig. 3 is an enlarged side view of the buckle and flap holding construction, said flap holding construction and the conveyor belt being shown in section;

Fig. 4 is a top view of the buckle construction shown in Fig. 3;

Fig. 5 is an enlarged fragmentary side view of the buckle construction and the flap locking member;

Fig. 6 is a detailed fragmentary view of another type of buckle construction made in accordance with the present invention;

2

Fig. 7 is a top view of the flap holding mechanism;

Fig. 8 is a fragmentary front view of said mechanism showing it in open position; and

Fig. 9 is an enlarged section through the buckle shown in Fig. 5.

Referring now especially to Figs. 1 and 2, it will be seen that the conveyor to which reference has herein been made comprises a canvas belt 10 which is provided with a plurality of transverse slats 11 and which is mounted on a pair of rollers 12 and 13, respectively. The canvas conveyor or belt 10 is not endless. Instead it has two ends which must be joined together by means of a buckle or other arrangement. In the present invention a buckle construction is used.

The buckle construction herein claimed to constitute an improvement over the prior art is shown very clearly in Figs. 3 and 4. The buckle construction actually comprises a plurality of such constructions, and in Fig. 1 it will be apparent that four may be employed on a single conveyor. For purposes of convenience, however, only a single one of these buckle constructions will be described, but it will be understood that any number of them may conveniently be used in connection with the conveyor belt.

A strap 20 is affixed by means of rivets 21 or by any other conventional means to the end slats 11 of one end of the conveyor belt. There is nothing critical about these last-mentioned number of slats, and strap 20 may be affixed not to two of said slats but only to one or perhaps to three. Affixed to the free end of the strap 20 is a buckle 22. It will be seen in Fig. 3 that this buckle is provided with a cam type of locking member 23, but it will be understood that this particular type of locking member is merely illustrative of the different types which may be used. A second

strap 25 is permanently affixed at one end to said buckle 22. Its opposite end is pulled or looped through a loop construction 27, and it is then brought back to and through buckle 22 where it is locked in place by cam member 23. The loop 27 may be of any suitable construction, and it really serves in the manner of a sheave or roller chock. In the construction shown in Figs. 3 and 4 the loop 27 comprises a plate 28 which is affixed by means of rivets 29 or by any other conventional means to the end slat 11 of the opposite end of the canvas belt 10, and which is provided with a transversely extending roller 30 spaced therefrom to form the loop through which the strap 25 extends. By way of reinforcing, a third

strap 35 is riveted at one end to the slat 11 which

lies adjacent the end slat 11 last-above mentioned, and which is connected at its opposite end by means of a hook and loop or bail construction 36 to the plate 28. The strap 35 strengthens the connecting bond between the plate 28 and the canvas belt, since it connects said plate to the second slat last-above mentioned.

The arrow in Fig. 3 indicates the direction in which the free end of strap 25 is pulled in order to tighten the canvas belt around its rollers 12 and 13 aforementioned. When the belt is mounted on its said rollers in the machine, the arrow shown in Fig. 3 points in the direction of the person engaged in tightening the belt around the rollers. It will thus be apparent that a pulling action is required in said operation rather than a pushing one which is the case with conventional buckle constructions. A greater force may be applied by means of the arrangement thus described, than is possible in conventional arrangements.

In Fig. 6 another type of loop construction is shown. Here strap 40 corresponds to previously described strap 35. The plate 41 which corresponds to plate 28 and which carries roller 42 which corresponds to roller 30 is not affixed, as will be apparent from Fig. 6, to any of the slats 11. Plate 41 is provided with a hook end 43 which engages a loop 44 which in turn is connected to the free end of strap 40 by means of fastening member 45. A more flexible connection is thereby provided than is the case with loop construction 27 above-described. The strap 25 is looped around the roller 42 in this construction in the same manner as in construction 27 above-mentioned.

The precise construction of the loop arrangement through which the strap 25 extends is not limited to the constructions shown in the drawing. Any conventional type of loop may be used. It is preferable, however, to use a loop having a roller for the reason that friction is thereby lessened between the strap and the loop. It will further be understood that although each strap 25 is shown to be provided with its own loop arrangement, a single loop arrangement for all of the straps 25 may also be used. There would be no substantial change in the construction of a loop of this type over the constructions shown in the drawing, except that the roller would extend the full width of the conveyor belt rather than the width of the individual straps used.

A flap 50 is formed at one end of the conveyor belt as shown in Fig. 3. This flap is really an extension of the belt itself, and its function is to cover the gap between the two ends of the belt as well as to cover the buckle construction by which the two ends are interconnected. In operation of the conveyor unit this flap ordinarily proves very troublesome, and it has been found very difficult to control or confine. A flap holding clip 60 has accordingly been provided to hold the flap 50 in its proper place. This clip is pivotally connected by means of plates 61 to one of the slats 11. As seen in Fig. 3, it is the second last slat at the buckle end of the binder canvas. Again this specific slat is not the critical one and other slats may be used to equal advantage for the purpose indicated. It has been found, however, that this particular slat may very conveniently be used as will hereinafter appear.

The clip 60 as shown in Fig. 7 is bent backwardly upon itself at its two ends, and it these backwardly extending portions that provide the pivotal connection between said clip and the

plates 61. These backwardly extending portions are bent substantially at right angles to the longitudinal axis of the clip to provide spring engaging members 62 which engage leaf springs 63. These leaf springs are affixed to said second slat 11 and the interconnection between said springs and said spring engaging members 62 is such that the springs normally urge the clip into the locked position shown in Fig. 5.

It will be noted in Fig. 7 that a groove 65 is formed in said second slat 11 to accommodate an inwardly extending bent center portion of the clip 60. When the clip is brought downwardly into its locked position, its bent center portion enters the groove 65 and there results a locking action between said groove and said clip. This locking action is in addition to that which is provided by the action of the springs 63 upon the bent ends 62 of the clip. When the clip is raised into its open position as shown in Figs. 3 and 8, the bent ends 62 engage the springs substantially at right angles hereto, and the spring action upon said bent ends is thereby cancelled out or prevented. To prevent the bent ends 62 from disengaging the springs when the clip is brought upwardly into its open position, a pair of flanges 69 is provided on each of said spring members 63. These flanges serve as stops for the bent ends 62 of the clip and prevent the disengagement thereof from said springs.

When clip 60 is used to confine or hold the flap 50, said flap is slipped under said clip when the clip is in its open position and the clip is then brought downwardly into its locked position. This may be seen particularly in Fig. 5. To a limited extent the inwardly bent center portion of the clip pushes the flap into the groove 65 and hereby locks said flap in position.

It will be noted in Fig. 5 that the clip 60 serves a double function. It not only holds the flap 50 but it also holds or confines the free ends of straps 25 after said free ends have been drawn through buckles 22. The clip 60 is shown in Fig. 7 to be provided with a plurality of raised or outwardly bent portions 67, one of said portions for each of straps 25. Recesses are thereby provided for the free ends of the straps 25. And it is in these recesses that the straps extend when the clip is brought downwardly into its closed position. Actually no direct contact is had between the clip and the straps 25 for the reason that the flap 50 is disposed between said clip and said straps. By reason of this fact the presence of the straps under the clip 60 when said clip is in closed position has the effect of urging corresponding portions of the flap 50 into said recesses 67. It is evident therefore that a double locking result is produced which affects both flap and the straps.

It will be understood that the foregoing constitutes a description of preferred embodiments of the invention and that modifications may be incorporated therein without departing from its spirit.

I claim:

1. In a device of the class described, a conveyor belt having ends disposed adjacent each other, adjustable straps connecting said ends to place the belt under proper tension, said belt having an integral flap extending from one end over the other end across a gap therebetween to cover the straps, a slat transversely disposed on the belt adjacent the free end of the flap, a wire clip mounted on said slat and extending along the length thereof and movable with respect thereto

to receive the end of the flap between itself and the slat, said clip adapted to be moved to an operative position to clamp the flap to the slat.

2. In a device of the class described, a conveyor belt having adjacent ends, adjustable straps connecting said ends to place the belt under proper tension, said straps having free ends extending across and onto one end of the belt, said belt having a flap extending across the gap between the ends of the belt and adapted to cover said straps and lying across the same end of the belt as the free ends of the straps, a slat transversely disposed on the last mentioned portion of said belt adjacent the end thereof, and a wire clip member pivotally mounted on said slat and extending lengthwise thereof and adapted to receive the free ends of the straps and the free end of the flap therebeneath, said clip movable to a locking position to hold the said free ends against the belt.

3. In a device of the class described, a conveyor belt having adjacent ends, adjustable straps connecting said ends to place the belt under proper tension, said straps having free ends extending across and onto one end of the belt, said belt having a flap extending across the gap between the ends of the belt and adapted to cover said straps and lying across the same end of the belt as the free ends of the straps, a slat transversely disposed on the last mentioned portion of said belt adjacent the end thereof, and a wire clip member pivotally mounted on said slat and extending lengthwise thereof and adapted to receive the free ends of the straps and the free end of the flap therebeneath, said clip movable to a locking position to hold the said free ends against the belt, the ends of said clip being bent at right angles to the length thereof and resting on top of the slat, and spring plates on the slat bearing against said bent ends to hold the clip in a normal locking position.

4. In a device of the class described, a conveyor belt having adjacent ends, adjustable straps connecting said ends to place the belt under proper tension, said straps having free ends extending across and onto one end of the belt, said belt having a flap extending across the gap between the ends of the belt and adapted to cover said straps and lying across the same end of the belt as the free ends of the straps, a slat transversely disposed on the last mentioned portion of said belt adjacent the end thereof, and a wire clip member pivotally mounted on said slat and extending lengthwise thereof and adapted to receive the free ends of the straps and the free end of the flap therebeneath, said clip movable to a locking position to hold the said free ends against the belt, the ends of said clip being bent at right angles to the length thereof and resting on top of the slat, spring plates on the slat bearing against said bent ends to hold the clip in a normal locking position, the surface of the slat having a groove therein, the clip member having a bent portion adapted to lie in said groove when the clip is moved to said locking position to hold said clip in said position.
